UNITED STATES PATENT OFFICE.

EUGENE AMBROZY, OF NEW YORK, N. Y., ASSIGNOR OF THREE AND ONE-HALF ONE-HUNDREDTHS TO LEOPOLD KRAFT, THREE AND ONE-HALF ONE-HUNDREDTHS TO CHARLES TÖRÖK, AND THREE AND ONE-HALF ONE-HUNDREDTHS TO JACOB WAGNER, ALL OF NEW YORK, N. Y.

BOAT CONSTRUCTION.

1,127,153.

Specification of Letters Patent.

Patented Feb. 2, 1915.

Application filed February 25, 1914. Serial No. 820,887.

To all whom it may concern:

Be it known that I, EUGENE AMBROZY, a subject of the King of Hungary, residing at New York, in the county of New York and State of New York, have invented certain new and useful Improvements in Boat Construction, of which the following is a specification.

This invention relates to ship building, and its primary object is to provide a hull structure having improved supporting and bracing means, to insure increased strength and rigidity, and to concentrate the impact and thrust-resistance at the longitudinal center of the vessel, and thus to equalize lateral strain.

The main characteristic feature of the invention is the employment of a vertically-disposed central partition wall or bulk-head, alined with the vessel's keel, and constituting a main central longitudinal stay extending throughout the length of the vessel, and serving as a central support for the side plating ribs, and their transverse bracing means.

The invention also includes improved means for rigidly connecting the several sections of which the main central stay or partition is composed, and for supporting the deck stanchions, ribs, braces, and other elements constituting the general structure of the ship's hull; and various detail features of construction, all of which will be fully described hereinafter, in connection with the accompanying drawings which form a part of this specification, and set forth and defined in the appended claims.

In the drawings: Figure 1 is a vertical longitudinal section of a portion of the bow of a ship embodying the invention. Fig. 2 is a horizontal section of the same. Fig. 3 is a vertical transverse section of the vessel illustrating certain of its inclined struts and braces in elevation. Fig. 4 is a vertical section on an enlarged scale taken on the line 4—4 of Fig. 2. Fig. 5 is a horizontal section on an enlarged scale, on the line 5—5 of Fig. 3 looking upward. Fig. 6 is a section on the line 6—6 of Fig. 2. Fig. 7 is a detail sectional perspective view, on the line 7—7 of Fig. 2. Fig. 8 is a detail elevation on an enlarged scale showing the manner of securing the

crossed struts or braces. Fig. 9 is a plan view, partly in horizontal section of the parts shown in Fig. 8. Fig. 10 is a fragmentary elevation of the lower portion of the vessel hull, the central partition being in transverse section, and showing a modified form of floor structure. Fig. 11 is a detail perspective view partly in section illustrating the angle plates employed.

The reference numeral 1 designates a vertical longitudinal partition supported centrally of the vessel's length, and dividing the interior of the hull into two compartments designated respectively by the letters A and B. This central longitudinal vertical partition extends throughout the length of the hull, and is made up of plate-sections, or units each comprising a plurality of 70 alined plates 2, connected and secured by the means hereinafter described.

As best shown in Fig. 3, the deck beams designated by the numeral 3 are supported by stanchions 4, which space them apart, and said beams are secured to the central stay or partition 1 by angle braces riveted to said partition and to the beams, as best seen in Fig. 6, the horizontal members 5 of said connecting braces being riveted to the beams, 80 and their vertical flanges 6 to the partition 1.

As best shown in Fig. 11, the plate sections 2 which make up the central longitudinal partition 1 abut one another side by side and at their ends, the end joints 7 being in staggered relation as shown in Fig. 2.

The plate sections 2 are held in proper relation to each other and are secured to the beams 3 by the angle brackets above described (see Fig. 11) each comprising the 90 horizontal member 5 and the vertical member 6 formed integral with the member 5 and having vertically-disposed slots 10 into which the floor beams 3 extend.

The angle plates comprising the members 95 5 and 6 are securely riveted as at 11 to both the central partition and to the several beams. On the underside of each beam 3 and secured thereto at the inner ends of said beams are angle plates 9, between which and the angle brackets 5—6 the floor beams 3 are held. See Figs. 3 and 6. As the connections for each floor of the structure with the central partition 1 are identical in construction,

it is not deemed necessary to specifically describe more than one of said floor supports or connections.

Any desired number of decks or floors 5 may be provided within the hull, the drawing showing a series of eight floors above the ship's bottom. At convenient points in the supporting partitions along the main thoroughfares on each deck are arranged doors 11^a.

10 The outer ends of the various deck beams 3 are suitably secured to the side plating of the vessel, and the latter is reinforced by any required number of stringers 12 firmly riveted to the plating and extending longitudinally throughout the length of the vessel between the decks or floors as clearly shown in Fig. 3.

15 The central vertical partition 1 is braced 20 to the transverse frames by a series of diagonally-disposed struts or braces 13 and 14 crossing each other firmly riveted together and to brace the sides of the vessel as well as the central partition 1.

20 Each of the decks is supported by the stanchions 4 as above stated as well as by knees 15, the latter being disposed in opposite directions on either side of the central partition 1 with their upper ends attached 25 to the deck beams 3, and having their lower ends bifurcated as shown in Fig. 5, for attachment to vertical angle members 15^a disposed between the floors and secured to the central bulk-head 1. In addition to the deck 30 beams 3 being supported by the central partition 1 and at their outer ends by the sides of the vessel, they are supported and braced intermediate the vessel sides and the partition 1 by the stanchions 4, and at the points 35 where the stanchions are provided, the deck beams are intersected by deck-stringers extending longitudinally of the vessel. Each 40 of these deck-stringers comprises (see Fig. 7) upper and lower angle-bars 17, an upper 45 bar and a lower bar being placed on each side of, and riveted to a vertical bar 19. At the points where the stanchions 4 intersect with these deck-stringers and the deck beams 3, said stanchions have disks or heads 20 50 (see Fig. 4) which are riveted to the angle bars 17 of the deck-stringers. The floors comprise spaced members 21—22 connected by inclined struts 23 disposed at opposite inclinations to afford rigidity of construction and brace the floors against strain in all directions. (See Fig. 3.)

55 As illustrated in Figs. 8 and 9, the several inclined braces 13 and 14 are off-set at their points of juncture shown at 24, thus adding 60 to the strength of their connection and adapting them to be secured to adjacent supporting members of the hull structure on opposite sides of the latter as shown in Fig. 8.

65 The specific construction of the angle

plates employed to connect the floor beams to the central partition 1 constitutes a feature of importance in the present invention, the slots in the vertical members of said angle plates receiving the floor beams as 70 above stated, and the horizontal members of said plates extending at right angles to the vertical members are in convenient position for their attachment to adjacent supporting parts.

75 A modified construction of the bottom of the vessel is shown in detail in Fig. 10 and is in the form of a double-floor, each formed of spaced upper and lower members braced by cross-struts 28, the upper and lower 80 floors being spaced apart by longitudinal I-beams 26 interposed between the floors.

85 From the construction as above described, it will be apparent that the central vertical longitudinal partition 1 constitutes the main support or foundation for all of the transverse beams which support the side plating, ribs, and floor supports, and that substantially all of the parts named may be 90 said to be suspended from such central longitudinal support. As shown in Figs. 3 and 10, the said central partition 1 is extended down so as to form the keel of the boat hull.

95 The central partition, beams, ribs, and other elements making up the hull structure are preferably covered with asbestos applied in any suitable manner, and I also 100 preferably provide a filling of concrete (not shown) between the floor members 21—22.

105 The improved construction affords rigid and substantial bracings for the vessel both laterally and longitudinally, all strains or impact being directed toward the longitudinal center of the hull.

Having thus fully described my invention and in what manner the same is designed for use, what I claim as new is:

1. A ship's hull, comprising the combination with the sides and bottom of the vessel, of a central vertically-disposed partition plate or bulk-head, and bracing means between said bulk-head and the sides, consisting of beams secured at their outer ends to the side plating and at their inner ends to said bulk-head by upper and lower complementary angle-plates, said upper plates having their vertical members slotted to receive the ends of the beams.

110 2. In a hull structure for ships, the combination with a central vertical longitudinal partition, of a floor having spaced upper and lower members, and inclined cross-struts connecting said members, said central partition extending downwardly to serve as 115 a keel.

120 3. A ship's hull, comprising the combination with the sides and bottom of the vessel, of a central vertical bulk-head, transverse deck-beams secured at their outer ends 125

to the sides of the vessel, and means for securing the inner ends of said beams to said central bulk-head, consisting of oppositely-disposed angle-plates having their horizontal members secured to said beams, and their vertical members to said bulk-head, and the upper of said plates being formed with slotted seats for the ends of the beams.

4. In a ship's hull, the combination with a central longitudinal partition or bulk-head, of means for securing and bracing the sides of the vessel to said bulk-head, comprising deck-beams secured at their outer ends to the side-plating of the vessel, and means for supporting and securing the inner ends of said beams, consisting of oppositely-disposed angle-plates secured to said bulk-head and beams, vertically-disposed plates

between said beams, and knees secured at their upper ends to said beams, and bifurcated at their lower ends and secured to said vertical plates.

5. In a ship structure, the combination with a central vertical bulk-head, of deck beams supported between the sides of the vessel and said bulk-head, a pair of spaced floors each made up of upper and lower plates connected by inclined cross-struts, and longitudinal I-beams between the floors.

In testimony whereof I affix my signature in presence of two witnesses.

EUGENE AMBROZY.
